UNITED STATES PATENT OFFICE.

THOMAS BOSTOCK, OF BROCKTON, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

MACHINE FOR PRESSING HEEL-LIFTS, HEELS, &c.

1,079,537.

Specification of Letters Patent.

Patented Nov. 25, 1913.

Application filed January 12, 1910. Serial No. 537,773.

To all whom it may concern:

Be it known that I, THOMAS BOSTOCK, of Brockton, in the county of Plymouth and State of Massachusetts, have invented certain new and useful Improvements in Machines for Pressing Heel-Lifts, Heels, &c., of which the following is a specification.

This invention relates to machines adapted for compressing heel lifts, heel, shanks, and other articles, and particularly for producing the pressed and ornamented toplift shown in the patent to W. F. Bostock, No. 907,723, dated December 29, 1908. In carrying this object into effect I provide a machine having pressing dies formed, adjusted and operated so as to impart the necessary degree of pressure to a toplift or a complete heel, and to impress at the same time the ornamental configuration illustrated in the patent above-noted.

In addition to the above, it is my object to provide in a machine of this character an automatic carrying mechanism for carrying lifts or heel blanks from the operator's station in front of the machine to the pressing position between the dies, and after the lifts or other articles have been pressed, to carry them from the pressing position into a discharging position.

Another object is to provide with a compressing machine of this general nature side blocks adjustable so as to closely embrace and confine the lift or other article, while the pressure of the dies is applied to its top and bottom surfaces, so as to retain the original shape of the article, while undergoing such pressure, but without themselves giving pressure to the edges of the article sufficient to condense it.

In the accompanying drawings I have illustrated a machine in which the objects of my invention and the principles thereof are carried into effect in the best manner at present known to me, it being understood that the machine as there shown and as hereinafter described is presented as illustrative merely of one form of working out of the invention, and not as a limitation to any particular form or embodiment.

In the drawings Figure 1 represents a front elevation of the machine hereinbefore referred to. Fig. 2 represents a vertical sec-

tion of the same on the line 2—2 of Fig. 1. Fig. 3 is a cross-section showing a detail of the feeding mechanism on an enlarged scale, 55 the section being taken on line 3—3 of Fig. 2. Fig. 4 is a plan view of the parts of the machine below line 4—4 of Fig. 1. Figs. 5 and 6 are plan views of the blocks forming part of a divided mold for confining the lift 60 or heel while being pressed, the former of these views showing the blocks separated and the latter showing them closed. Fig. 7 is a sectional view of the pressing members showing them closed upon a lift. Fig. 65 8 is a sectional view of the same members showing them separated with a lift in place between them, after having been compressed. Fig. 9 is a detail elevation of one of the gripping means forming part of the 70 feeding device and of the means for opening the same, this view showing such gripping means in closed position. Fig. 10 is a sectional plan view of the same on line 10—10 of Fig. 9. Fig. 11 is a view similar 75 to Fig. 9, but showing the parts in open position. Fig. 12 is a sectional plan view on line 12—12 of Fig. 11. Fig. 13 is a plan view of a modified form of feeding gripper.

The same reference characters indicate 80 the same parts in all the figures.

The base portion of the machine comprises side frames 1 and 2 connected by cross beams 3 and 4. Guide rods 5, 5 and 6, 6 are stepped in the side frames and rise 85 above the same, supporting at their upper ends a rigid cross-head 7, which is normally stationary. Guided on the rods 5 and 6 is a moving cross-head 8 operated from a power shaft 9 through a crank 10, pitman 90 or connecting rod 11, and toggle levers 12, 13, the latter having knuckle 14 with which the pitman has a wrist connection.

The cross-heads 7 and 8 carry compressing dies or pressers 15 and 16, between 95 which a toplift, or if desired, a complete heel is placed and by which it is compressed on the top and bottom surfaces. The die 15 is contained in a holder 17, having a T-slot 18 receiving the head of the die. This holder 100 is secured by a rod 19 passing through the fixed cross-head 7 and is adjusted by a wedge 20 contained between the under surface of the cross-head and the upper sur-

face of the holder. This wedge is adjustable so as to vary the height of the die 15 by a screw 21, as shown in Fig. 2.

The die 16 or movable presser is carried 5 by the cross-head 8 and reciprocated toward and from the fixed die. Said die 16 is the block yieldingly held by the cross-head 8, preferably by being secured upon a stem 22 which is supported by a spring 23. The 10 movement of the stem is limited by a pin 24 on the latter, projecting through a slot 25 in the cross-head. The die 16 is held projected by the spring 23 at all times except when pressed against a lift contained 15 between it and the fixed die 15. At these times the spring 23 yields until the die 16 reaches a plate 26 which affords a rigid abutment. The height of this plate is adjusted by a wedge or shim 27, which is positioned by a screw 28. By adjusting the 20 wedges 20 and 27, the distance apart of the dies when in their ultimate positions may be varied to accommodate lifts or heels of varying thickness and to secure the desired degree of compression.

As this machine is designed to form the toplift shown in the patent before referred to, or to form a heel having a similarly ornamented tread surface, one of the dies, as 30 the die 16, is made in such form as to produce a surface having the characteristic features as noted in the said patent. This formation of the die is shown best in Figs. 7 and 8, the central part *a* of the acting surface of the die being cut to produce the desired ornamentation in the lift or heel, and the edge portion *b* being depressed to cause the surface of the lift or heel at the edge thereof to be raised. The relation of the 35 dies 15 and 16 to one another may, of course, be reversed, the former die having the ornamented and recessed surface and the latter being plain, without departing from the spirit of my invention.

40 The die 16 is contained in a recess in the cross-head 8, between a fixed lip 29 formed thereon, and blocks 30, 31. The lip 29 provides a gage or guide for the breast of the lift or heel, while the blocks 30 and 31 are 45 recessed to fit the periphery of the die block 16 and of the lift or heel thereon. These blocks thus constitute the two halves of a divided mold which confines the periphery of the heel and prevents it from spreading 55 when the pressure is applied.

The members of the mold are brought 60 together to engage the lift when the pressure is applied and are separated when the pressure is removed, in order to permit ready removal of a pressed lift and insertion of a new one. The approach and recession of the 65 parts of the mold toward and from one another are controlled by the movements of the cross-head 8 in bringing the dies into and out of pressing relation. For this pur-

pose the blocks 30 and 31 are arranged to slide upon the cross-head 8 along the lip 29, which thus at one time acts as a guide for the blocks and as a gage for locating the breast of the heel lift. Pivoted 70 connected to the blocks 30 and 31, or rather to separate blocks 32 and 33 (which latter are connected to the blocks 30 and 31 by straps 34, 35) are links 36 and 37, the outer ends of which are connected respectively 75 to bars 38 and 39. The links are so placed that when the cross-head is elevated into its uppermost position the blocks 30 and 31 are brought together against the rim of the heel or lift, and as the cross-head descends, the 80 increasing angularity of the links causes the blocks to be drawn apart. These blocks are so made that they will not condense the lift, but will maintain its original shape. Preferably the arrangement is such that when 85 the movable cross-head is in its extreme upper position, the links 36 and 37 are approximately in line. The distance apart of the blocks may be accurately adjusted and either or both blocks shifted to center 90 them by means which shifts the position of the bars 38 and 39, one such means being shown in Fig. 1. As here shown the bars are pivoted at their lower ends to the side frames of the machine base, so that their 95 upper ends may swing toward and from one another. The upper end of each bar passes into a slot in the fixed cross-head and is engaged by a screw or bolt 40 threaded into the arm and having a head bearing against 100 the end of the cross-head. A wedge 41 is inserted between the arm and the adjacent end of the cross-head and is adjusted up or down by a screw 42. By this adjusting means the positions of both bars and therefore of the mold blocks may be readily and accurately adjusted. Thus the parts of the 105 mold may be set so that when nearest together they conform exactly to the original form of the lift as died from the leather, 110 without either compressing the lift edgewise, or allowing it to spread, for it is the object of this part of my invention to preserve the lift after compression of the same size and shape as given it by the cutting die, 115 without either compressing it edgewise or allowing it to expand.

One of the main features of the invention is a carrier which is automatically operated 120 to carry blanks from the operator's station into pressing position between the dies, and then to remove the lifts or heels after being compressed, and carry them into a position from which they may be delivered to a discharge spout. By virtue of this feature of 125 the invention, the operator of the machine has nothing more to do than merely place the blanks in the carrier, the location of the blanks between the dies and the discharge of the compressed articles from the machine be- 130

ing accomplished by the carrier at the proper time automatically. The carrier consists of a head 43, from which project two or more heel-grasping devices 44. The latter project 5 horizontally from the head over a table 45, which is secured to the cross-head on a level with the end of the die 16 when the latter is projected as shown in Fig. 2. These blank-grasping devices 44 consists each of 10 two jaws 46, 47, pivoted to the head 43 and formed at their outer ends into the shape of the periphery of a heel. On each jaw is fastened a segmental cheek 48, made to fit accurately about one half of the curved part of 15 the heel. The jaws also have breast pieces 49 from which project ears 50. The jaws of each gripper are normally held together by a spring 51, while any movement which they may have is given equally to each by means 20 of a tooth 52 on one jaw near its pivot, engaging a notch similarly located on the other jaw.

The carrier and the grippers connected therewith are given a step-by-step rotary motion during the rising and falling movements of the cross-head 8, from a shaft 53, which has a like motion. A squared or otherwise non-circular end 54 on the shaft projects into a correspondingly shaped 25 opening in the head 43 so as to communicate motion thereto. The shaft 53 is held in a bearing 55 integrally or otherwise secured to the moving cross-head 8, and a collar 56 fastened to the shaft above this bearing 30 causes the latter to rise when the cross-head rises. The lower end of the shaft is guided in the cross-bar 3 so as to be held steady, but not to be prevented from up and down motion. Rotary movement is given to the 35 shaft 53 from the main drive shaft 9 through a rack 57 confined in a guide 58 (see Fig. 1) and reciprocated by a connecting rod 59 engaged with a crank pin 60 on a disk 61, which is secured to the end of the 40 shaft 9. This rack engages a pinion 62, journaled in bearing brackets 63 and 64, which project from the side frame 2. With this pinion is also engaged a second rack 65 held in a guide 66, which extends transversely of the machine from one side frame 45 to the other. The latter rack meshes with a wide-faced pinion 67 mounted loosely upon the shaft 53. This pinion is supported at its lower end by a collar 68 pinned to the 50 shaft so that it is compelled to rise and fall with the latter. It is sufficiently long to remain in mesh with the rack 65 in both limits of travel of the cross-head. Secured to the pinion 67 is a pawl carrier 68^a carrying a 55 pawl 69. The latter engages a wheel or disk 70 rigidly secured to the shaft which has as many notches and teeth as there are lift grippers 44, in this case four. The ratchet 70 is formed as a flange on a sleeve 71, which 60 surrounds the shaft 53 and is secured thereto

by any suitable means, as by a set screw 72. As the shaft 9 rotates, the racks 57 and 65 are reciprocated, thereby oscillating the pinion 67. This imparts a step-by-step rotation to the shaft 53 through the pawl and ratchet just described. Thereby the grippers 44 are moved step by step from the front of the machine where the operator stands, into a position between the pressing dies and thence over a discharge spout indicated by dotted lines in Fig. 4 and designated by the numeral 73. On the fixed cross-head are secured pointed bars 74 and 75, one directly in rear of the die 15 and the other at the left of the machine, as 70 shown in Fig. 1. These bars are located so that their pointed ends will enter between the tongues or projections 50 of those lift grippers which are located respectively between the pressing dies and over the discharge spout. Thus the gripper which holds the blank ready for pressing is opened to admit the die 15, and the gripper holding a compressed lift or heel is opened to permit such article to fall upon the discharge spout 75 80 85 90 and thence into a receptacle.

From the foregoing description the operation of the machine will be readily understood. The operator stands at the front where he can press heel lifts and blanks 95 into the gripper which is shown in Fig. 4 projecting toward the front of the table. As each gripper comes to the front empty, the attendant places a toplift or other article in it, the upper edges of the cheeks 48 100 being beveled as shown in Figs. 7 and 8 to permit ready insertion of these articles. In each double reciprocation of the cross-head the carrier is fed one step, thereby carrying a filled gripper over the die 16 and under 105 the die 15. This movement occurs while the dies are separated, the operating mechanism being timed to turn the shaft and lift-carrier while the movable cross-head 8 is descending. As the cross-head 8 rises, the projections 50 on the lift-holder at the rear engage the pointed end of the bar 74 and are 110 separated, allowing the lift to rest on the die 16 between the blocks 30 and 31 of the mold. When the lifts are brought against the fixed die, the die 16 is caused to yield against the spring 23 until it brings up 115 against the fixed abutment plate 26, thus allowing the lift to be brought between the parts of the mold and allowing the latter 120 to be closed upon the edges of the lift. As the cross-head descends the spring 23 holds the die 16 up until the table and carrier have descended far enough for the gripper to embrace the lift, and subsequent depression in 125 the cross-head allows the jaws of the gripper to descend clear of the bar 74 and to close upon the lift as they are thus released from the bar 74. Then the gripper which was last between the dies is carried to the 130

discharging position by the intermittent feed mechanism. Upon the next upward travel of the cross-head 8 the jaws of this gripper are again opened, this time by the bar 75, which allows the lift or other article to drop from the gripper and escape. It is within the contemplation of my invention also to provide another bar similar to the bars 74 and 75 in a position opposite to the latter bar, that is at the opposite side of the lift carrier and symmetrically arranged with respect to the bar 75. Such additional bar would be located to open the gripper shown at the right-hand side of Fig. 1 and in the upper part of Fig. 4, so that when thus opened a lift or heel might be dropped between this pair of grippers by the attendant of the machine.

In Fig. 13 is shown a modified form of gripper which is provided with means for taking lifts or heels of any size. Upon the jaws 46 and 47 of the gripper are adjustable fingers 461, 462 and 471, 472 respectively. These fingers are slotted and are secured to the jaws by screws passing through their slots. Thus they may be moved in or out with respect to the article-receiving space between the jaws.

It will be seen that the machine is entirely automatic in its action, except for the single detail of putting the lifts or other articles in the grippers of the carrier, and that the lifts are brought to the compressing dies and carried therefrom at the proper times without danger of injury.

I claim—

1. The combination in a compressing machine of coöperating opposed dies, means for forcing one of the dies toward the other, and withdrawing it therefrom, a carrier having means for grasping an article to be compressed mounted to travel between the dies in a path transverse to the direction in which the pressure of the dies is applied, mechanism for moving said carrier step by step constructed to cause the carrier to be arrested when the article carried thereby is between the dies and at the time when the dies are in position to press upon the article, means for causing the grasping means of the carrier to release the article when so arrested, and means for causing the article to be again grasped when the dies separate, whereby a further movement of the carrier removes the compressed article from between the dies.

2. The combination in a compressing machine of coöperating opposed dies, means for forcing one of the dies toward the other, and withdrawing it therefrom, a carrier having means for grasping an article to be compressed mounted to travel between the dies in a path transverse to the direction in which the pressure of the dies is applied, means for causing said grasping means to

release the article when between the die, and to grasp the article again after compression, and mechanism for advancing the carrier step by step, said mechanism being constructed to cause an arrest of the carrier when the article is between the dies and the latter engage the article, and to advance the carrier farther when the dies separate.

3. The combination of a pair of opposed dies having their adjacent operative faces approximately flat, means for moving one of the dies toward and from the other, a carrier having separable grippers for grasping the edges of an article which has approximately flat faces, said carrier being mounted to travel in a path extending between the dies and substantially parallel with the operative faces thereof, means for advancing the carrier with a step by step motion and causing the same to pause while the article is between the dies and the latter are most closely together, and means for separating said grippers.

4. The combination in a press machine of the character described, of coöperating dies, a carrier having means for grasping an article to be pressed, mechanism for moving said carrier step by step to carry the article into pressing position between said dies and remove it therefrom to a discharging position, and means for causing said grasping means to release the article temporarily while between the dies.

5. A machine comprising compressing elements or dies, mechanism for producing a relative movement of approach and recession between the dies, a rotary carrier for the articles to be compressed consisting of a plurality of holders radiating from the axis of rotation, such axis being approximately parallel to the line of movement of the dies and so located that the holders pass between the dies and close to one of them, means for rotating the carrier step by step and arresting it when any holder is between the dies, and means other than such holder for confining the periphery of the article between the dies.

6. A compressing machine comprising coöperating pressing dies, mechanism for moving one of said dies toward and from the other, a carrier having grasping elements to hold the article to be compressed, mechanism for moving said carrier to bring the grasping elements thereof into and out of position between said dies, means for causing said grasping elements to release the article when the dies are in action, and means for causing said grasping elements again to take the article when the dies separate, whereby the article may be removed from between the dies upon further travel of the carrier.

7. A compressing machine comprising coöperating pressing dies, mechanism for

moving one of said dies toward and from the other, a carrier connected to and movable with said movable die having a plurality of outwardly-extending lift-grasping elements constructed and arranged to embrace the periphery of a lift, and mechanism for moving said carrier rotarily with a step-by-step motion about an axis approximately parallel with the line of motion of said die, to bring said grasping elements into position to hold a lift between said dies and to remove the same therefrom.

8. A machine for compressing heel lifts and the like, comprising a fixed die, a movable die-carrier, means for moving said carrier toward and from the fixed die, a die mounted on said carrier in line with the fixed die and adapted to press lifts against the latter, a lift carrier supported by said die carrier and movable therewith, said lift carrier being arranged to rotate about an axis parallel to the line of movement and having a lift-holding portion arranged to pass directly over the moving die, and mechanism for rotating the lift carrier step by step while the die carrier is in motion arranged to arrest such rotation when the lift-holding portion is between the dies and the latter are most closely adjacent, whereby the lift-carrier is enabled to place a lift in pressing position and remove it after compression by successive steps.

9. A machine for compressing heel lifts and the like, comprising a fixed die, a movable die-carrier, means for moving said carrier toward and from the fixed die, a die mounted on said carrier in line with the fixed die and adapted to press lifts against the latter, a lift carrier having a plurality of lift-holders movable between the dies, mechanism for so moving the lift carrier as to place the holders successively between the dies while the latter compress the lifts, and means for causing the dies to remove the lifts from the holders during compression, and to return them to the holders when compressed.

10. A machine for pressing heels, lifts, and the like, comprising a pair of co-operating dies relatively movable in line together and apart and adapted to act on the top and bottom faces of the heel or lift, a carrier having concave separable grippers constructed to hold the edges of a heel or lift and movable rotarily in a path transverse to, and between, said dies, means for causing separation of said grippers when between the dies to release the lift, and mechanism for rotating said carrier step by step, said mechanism being so timed that the carrier is caused to place a heel or lift in pressing position between the dies, to pause while the dies act, and then to remove the heel or lift from between the dies.

11. A machine for compressing heel lifts and the like, comprising a pair of co-operating pressing dies, means for moving one of said dies toward and from the other to compress a lift placed between them, recessed blocks on opposite sides of said dies together forming a mold adapted to embrace a lift placed between said dies, said blocks being carried with the movable die, stationary abutments each pivotally mounted at one end, links connected with said blocks and with said abutments at a distance from the pivoted ends thereof in such manner that they approach alinement when the movable die approaches the fixed die, and are brought out of alinement when the movable die recedes, whereby said blocks are alternately brought together and separated as the lift is subjected to pressure and released, and means for adjusting the free ends of said abutments toward and from the line of motion of said die to cause the mold formed by said blocks to conform exactly with the original size of the lift when said blocks are nearest to each other.

12. A machine for compressing heel lifts, heels and the like, comprising a pair of co-operating pressing dies adapted to bear on the faces of the lift or heel, mechanism for moving one of said dies toward and from the other, recessed blocks on opposite sides of said dies together forming a mold adapted to embrace the edges of the lift or heel, mechanism including pivoted bars arranged to swing toward and from said dies for causing said blocks to approach and recede from each other when the dies are respectively moved together and apart, and wedges engaging said bars on the outer sides thereof for adjusting the positions of said blocks to cause them when most closely adjacent to one another to conform exactly with the original size of the lift or heel before compression thereof.

13. A machine for compressing lifts and the like, comprising co-operating pressing dies, one of which is movable toward and from the other, a lift carrier having a plurality of lift-holding means independent of both dies, mechanism for moving said carrier a step at each operation of the machine, the said carrier being so constructed and the steps of its movement so spaced that at each step thereof one of the lift-holding means is between the dies holding a lift ready to be compressed, a second holding means is clear of the dies in discharging position, and a third holder is in position to be filled, and means for causing the holding means which is in discharging position to release its lift.

14. A machine for compressing lifts and the like, comprising co-operating pressing dies, one of which is movable toward and from the other, a lift carrier having a plurality of lift-holding means, mechanism for moving said carrier a step at each operation

of the machine, the said carrier being so constructed that at each step of its movement, one of the lift-holding means thereof is between the dies, means operative when the dies are brought together for releasing the lift from the last-named holder, and provisions for causing said holder to again engage the lift after compression thereof, to enable a subsequent step of the carrier to remove said lift from between the dies.

15. A machine for compressing lifts and the like, comprising coöperating dies, one of which is movable toward and from the other, a lift carrier having a plurality of lift-holding means, mechanism for moving said carrier a step at each operation of the machine, the said carrier being so constructed that at each step thereof one of its holding means is brought between the dies and another holding means is displaced therefrom, and means rendered operative upon each actuation of the dies for causing the holding means between the dies to release its lift and for causing the holding means last removed from the dies also to release the compressed lift held thereby and permit the same to be discharged from the machine.

16. A machine for compressing heel lifts and similar articles, comprising coöperating pressing dies, mechanism for moving one of said dies toward and from the other, a lift carrier including a pair of jaws adapted to grasp a lift or similar article between them, resilient means tending to hold said jaws in grasping position, mechanism for moving said carrier so as to place said jaws between the dies intermediate the compressing movements thereof, and a device fixed in such relation to one of the dies as to be operative when said dies are brought into pressing relation to enter between and separate said jaws and cause the lift to be released.

17. A machine for compressing heel lifts and similar articles comprising a pair of co-operating pressure dies, a support for each of said dies, means for reciprocating one of said supports and the die associated therewith toward and from the other die, one of said dies being mounted yieldingly upon its support so that it may yield a limited distance after engagement with a lift placed between the dies, a mold mounted on the support for said yielding die embracing the latter, a lift carrier having resiliently actuated grasping jaws movable into and out of position between said dies, and means for separating and holding said jaws apart while a lift is engaged by the dies, the yielding die being re-projected as the separation between the dies occurs to place the compressed lift again between said grasping jaws, whereby further movement of the carrier is enabled to remove the lift from between the dies.

18. A machine for compressing heel lifts

and similar articles comprising a fixed support or cross-head, a die attached thereto, a moving support or cross-head, a die carried thereby, mechanism for moving the last-named cross-head toward the other, a lift carrier having resiliently actuated grasping jaws movable into and out of position between said dies, and a projecting cam member having diverging edges or sides carried by one of said cross-heads arranged to pass between said jaws and separate them when the dies are brought together upon a lift presented by the jaws, the said jaws being allowed again to grasp the lift upon separation of the dies.

19. A machine for compressing heel lifts and similar articles comprising a pair of dies adapted to engage the opposite sides of the lift, means for moving one of said dies toward and from the other, a lift carrier connected and movable with the movable die, and having means independent of either die for holding a lift, said carrier being additionally movable step by step rotarily for placing lifts between the dies and removing them therefrom, and means for so moving said carrier.

20. A machine of the character described, comprising coöperating dies, one of which is movable toward and from the other, mechanism for so moving said die, a carrier connected and movable with said movable die and operable transversely to the movement of said die in a path extending between the dies, a rack moved reciprocally by said die-operating mechanism, and pawl and ratchet mechanism operated by said rack and acting upon said carrier for rotating the latter step by step, said mechanism being constructed to move with the die relatively to said rack.

21. In a machine of the character described a pair of coöperating dies, one of which moves toward and from the other, a lift carrier movable simultaneously with the movable die and having a secondary movement in a direction transverse to that of the die for placing the article to be pressed between the dies and removing it therefrom, and means operative to give said secondary movement to said carrier while the carrier has its primary movement, comprising a pawl and ratchet mechanism connected with said carrier, a rack, and a coöperating pinion, one of which has a wide face and is movable with the die and lift-carrier relatively to the other, and means for reciprocating such rack.

22. In a machine of the character described having a pair of dies, one of which is movable reciprocatively toward and from the other, a lift-carrier movable transversely to said dies for carrying lifts into and out of pressing position between the dies, and means for moving said carrier step by step,

- comprising a pawl and ratchet mechanism, a pinion connected to one element of said mechanism, the other element being connected to the carrier, a rack meshing with 5 said pinion, a second rack, an intermediate pinion with which both racks are in mesh and by which one operates the other, and mechanism for simultaneously reciprocating one of said racks and said movable die.
23. In a heel-compressing machine a pair of dies, mechanism for reciprocating one of said dies toward and from the other, a lift-carrier movable with said reciprocating die and having a secondary motion transverse 10 thereto for placing heels or lifts between the dies and removing them therefrom, and mechanism for giving said carrier its secondary motion intermittently, consisting of a pawl and ratchet, a pinion connected to 15 said pawl and ratchet mechanism and a reciprocating rack in mesh with said pinion, the pinion having a wide face in longitudinally sliding mesh with such rack, whereby 20 to permit the movement of the carrier with the die simultaneously with its transverse 25 feeding movement.
24. In a machine for compressing heel lifts, heels and the like, a stationary die, a movable die arranged to reciprocate toward 30 and from the said fixed die, a lift or heel-carrier reciprocating with said movable die and also movable transversely thereto to place lifts in and remove them from position 35 between the dies, said carrier including a pair of spring-pressed grippers, and means associated with the fixed die arranged to enter between and separate said grippers when the lift-carrier between the dies approaches the fixed die.
25. The combination in a machine of the character described, of a relatively stationary die, a cross-head movable toward and from said die, a relatively movable die carried by said cross-head, yielding means tending 40 to project the movable die from the cross-head toward the stationary die, a bottoming plate loosely arranged beneath the movable die, and means for adjusting said plate toward and from the stationary die, whereby 45 to accommodate lifts of varying thicknesses and to vary the intensity of pressure exerted.
26. The combination in a machine of the character described, of a relatively station- 50

ary die, a cross-head movable toward and from said die, a relatively movable die carried by said cross-head, yielding means tending to project the movable die from the cross-head toward the stationary die, a wedge interposed between the movable die and the thrust-applying surface of the cross-head, 60 and means for adjusting said wedge to vary the possible extent of movement thereof relatively to the cross-head.

27. The combination in a machine for pressing heel lifts, heels, etc., of a relatively stationary die, a head movable toward and from said die, members constituting a mold carried by said head, a relatively movable die carried by the head between said mold members, yielding means tending to project 70 the movable die out of the mold toward the stationary die, and permitting it to be pushed into the mold by the resistance of the article being pressed, an abutment plate loosely fitting the mold cavity under the 75 movable die, and an adjustable wedge between said plate and the adjacent face of the wedge for limiting the extent to which the movable die may be retracted, and thereby the degree of pressure exerted on the article. 80

28. A compressing machine comprising complementary, opposed, coöperating pressing dies, one of which is movable toward and from the other, and one of which is mounted with ability to yield relatively to the other, 85 mold members flanking said yielding die formed to fit about the periphery of the article to be compressed, whereby to prevent spreading of the article under compression, means for carrying said movable die toward 90 and from the other die, an article carrier, and means for bringing said carrier between the dies when the latter are separated and causing said carrier there to pause, the article being displaced from the carrier by the pressure of one die and the yielding of the other 95 into the space between said mold members, and being returned to the carrier by return of the yielding die.

In testimony whereof I have affixed my 100 signature, in presence of two witnesses.

THOMAS BOSTOCK.
